C. C. GATES

ROOF

Filed June 16, 1923

Charles C. Gates Inventor

By *N. E. Geesey* Attorney

UNITED STATES PATENT OFFICE.

CHARLES C. GATES, OF ALTOONA, PENNSYLVANIA.

ROOF.

Application filed June 16, 1923. Serial No. 645,771.

To all whom it may concern:

Be it known that CHARLES C. GATES, a citizen of the United States, residing at 3322 Beal Ave., Altoona, in the county of Blair and State of Pennsylvania, has invented certain new and useful Improvements in Roofs, of which the following is a specification.

This invention relates to roof coverings, and has particular reference to that type of covering known as composition roofing, wherein the sheets of the roofing material are laid and fastened to the supporting surface in the ordinary manner of laying slate shingles, and the primary object of this invention is to provide a roof covering wherein the shingles are laid and held on the roof by a shingle clip, that is adapted to hold a plurality of shingles on the roof and to engage the outer shingle such that the wind cannot turn the edges up as is often done with roofing of this character.

Another object of this invention is to provide a shingle that has an integral rectangular weather strip adapted to be positioned at the top of the shingle, and lie immediately beneath the joint between the shingles when the same are laid in position on the roof.

A further object of this invention is to provide a shingle that when laid on the roof and secured in place thereto, the edges of the shingles form a series of squares that run diagonal across the roof, thus adding greatly to the neatness and attractiveness of the roof.

A still further object of this invention is to provide a metal clip that is adapted to envelope the downwardly projecting point of the outer shingle and to hold the same against the shingles immediately beneath.

With these and many other objects in view which will be more readily apparent as the nature of the invention is better understood, the same consists in the novel construction, combination and arrangement of parts as will be hereinafter fully pointed out, illustrated and claimed.

It will be quite apparent to those skilled in the art to which this invention belongs that the same is susceptible of various changes and modifications without departing from the spirit or scope of the invention, but a preferred and thoroughly practical embodiment of the invention is shown in the accompanying drawings in which:—

Figure 1 shows a plain view of my im-

proved roof having my shingle clips applied thereto.

Figure 2 shows a plan view of one of the shingles that are used in constructing the roof.

Figure 3 shows the manner of applying the shingles to the roof.

Figure 4 shows a plan view of the shingle clip which is shown applied to the roof in Figure 1 of the drawings.

Figure 5 is an edge view of the shingle clip shown in Figure 4 of the drawings.

Similar reference numerals refer to similar parts throughout the several figures of the drawings.

In carrying out this invention I provide a shingle designated by the numeral 10, having an apex 11 and a rectangular wing 12 positioned opposite the apex.

At right angles to a line bisecting the wing and drawn through the apex converging truncaed sides are formed as shown in Figure 2 of the drawings.

In laying the shingles 10 on a roof the pointed lower ends thereof are positioned in a metal clip designated as 13 and having the upturned wings 14 and 15 for embracing the sides 16 and 17 of the shingle. Each upper row of shingles has its lower edges 16 and 17 overlapping the upper edges of the shingle in the next row below as shown in Fig. 3 so that the abutting flat corners of adjacent shingles meet over the weatherstrip portion 12 of the shingle beneath. The clip 13 may then be placed over the joint formed by the flat meeting edges of adjoining shingles and also over the said strip thereby to receive fastenings which will pass through the spaced openings 18 and 19 in the clip. As shown in Figures 3 and 4 the spacing of the openings 18 and 19 is such that the fastenings will not pierce the weatherstrip, thereby avoiding puncturing of said strip. The shingle clip 13 is further provided with a plurality of perforations 18 and 19 through which nails or other attaching means are adapted to pass thus holding in addition adjacent shingles in position as shown in Figure 3 of the drawings.

The shingle clip designated by the numeral 13 is provided with upturned wings 14 and 15 which engage the edges of the shingle, while between the wings sufficient opening is provided for the escape of any foreign matter that may be collected on the shingle. In setting the shingle in the clip sufficient

allowance is made for ample contraction and expansion of the shingles to prevent warping of the latter on the roof.

From the construction of the shingle 10 it will be observed that no waste material is obtained when cutting the shingles out of the sheet and further it will be observed that the shingles when bisected form a very convenient method of finishing the edges of the roof and that roofs constructed in accordance with this invention will be attractive, durable and economical.

Having thus described my invention, what I claim and desire to be secured by Letters Patent is:

1. A roof shingling construction including a shingle having a body adapted to be laid to the weather and having a tip formed at one corner thereof and a relatively narrow weather strip formed opposite said tip, and

a plate-like clip for overlying said strip and including a body having fastening receiving openings, and said clip having the converging edges thereof formed with reversely folded spaced apart wings for receiving the tip of the next shingle above. 25

2. A roof shingling construction including a shingle having a body adapted to be laid to the weather and having a tip formed at one corner thereof and an elongated rectangular weather strip projecting from the opposite corner thereof, and a plate-like clip for overlying said weather strip and including a body having fastening receiving openings spaced apart to avoid the piercing of the said strip by the fastenings, and means at the lower edge of the clip for receiving the tip of the next shingle above. 30 35

In testimony whereof I affix my signature.

CHARLES C. GATES.
